UNITED STATES PATENT OFFICE.

JOSEPH SAUER AND JOSEPH SCHINDEL, OF PHILADELPHIA, PENNSYLVANIA.

DESIGN FOR A BALLOON TOY.

Application filed February 23, 1926. Serial No. 16,647. Term of patent 14 years.

To all whom it may concern:

Be it known that we, JOSEPH SAUER and JOSEPH SCHINDEL, citizens of the United States, residing at Philadelphia, in the county of Philadelphia and State of Pennsylvania, have invented a new, original, and ornamental Design for Balloon Toy, of which the following is a specification, reference being had to the accompanying drawing, forming part thereof.

The figure of the drawing is an elevation showing our new design.

We claim:

The ornamental design of a balloon toy substantially as shown and described.

JOSEPH SAUER.
JOSEPH SCHINDEL.
